Inventor:
Karl W. H. Schroeder

By: A. Singer, Atty.

UNITED STATES PATENT OFFICE.

KARL WILHELM HEINRICH SCHROEDER, OF LEIPZIG-REUDNITZ, GERMANY.

IMITATION WATERFALL.

1,399,662.

Specification of Letters Patent.

Patented Dec. 6, 1921.

Application filed December 10, 1920. Serial No. 429,743.

To all whom it may concern:

Be it known, that I, KARL W. H. SCHROEDER, a citizen of the German Republic, and a resident of Leipzig-Reudnitz, 5 Saxony, Germany, have invented certain new and useful Improvements in Imitation Waterfalls, Especially for Advertising Purposes, of which the following is a specification.

10 It is a well known fact that the attention paid by the public to show-windows, advertising devices and the like is considerably increased if movement is produced within the same. This is obtained in the subject 15 matter of this invention by very simple means in such a manner, that an imitation of a water-play, for instance a fountain emitting a jet of water, is produced.

On the rear or back-side of a fountain-like 20 shaped advertising device or on the back-side of an advertising picture, displayed in a show-window, a receptacle is disposed, which is not visible to the observer and which is filled with finely granulated sand. On the 25 lower end of this receptacle a suitably shaped discharge-aperture, nozzle or the like, which preferably is made as small as possible and which terminates in the front face of the picture or in that side of the advertising device, which is turned toward the observer is provided. From this discharge-aperture 30 the finely granulated sand flows out and dribbles down in the form of a jet, so that it produces the impression of a jet of water and thereby confers to the picture or advertising device a movement, which attracts 35 the attention of the observer. The jet can emanate from the mouth of a lion, or from the relief of a fountain, represented on the advertising or from such a representation of the advertising picture, whereby the impression of the flowing jet of water is still increased.

The discharge aperture further can be 40 arranged in such a manner, that the apparent jet of water flows toward a certain point of the advertising device or picture, to which the attention of the observer is to be especially directed.

45 In the accompanying drawing, in which one embodiment of the subject matter of my invention is illustrated,

Figure 1 is a front view of my novel device and

Fig. 2 is cross section of the same on line 55 I—I of Fig. 1.

In the drawings 1 indicates the pillar, which is shaped in the form of a fountain and is provided with the fountain-trough or basin 2, the funnel-shaped receptacle 3 arranged above said basin on the back-side of the pillar and serving to receive the finely granulated sand, which shall dribble down, and with a nozzle, arranged in an incision of the front side of the pillar near the lower 60 end of the funnel shaped receptacle. This nozzle consists in this embodiment of the subject matter of my invention of a piece of sheet metal 4, provided with horizontal transverse slots 5, which are produced between tongues punched out of the metal and 70 bent toward the inner side of the receptacle 3. Under the over-pressure prevailing within said receptacle the sand dribbles down over the distributing ledge 6 of the 75 nozzle 4 into the basin 2 and from there through an opening 7 into a receptacle 8, from it which it can be removed and again filled into the receptacle 3.

Having thus particularly described the 80 nature of my invention, what I claim as new and desire to secure by Letters Patent of the United States is:

1. A device for imitating a water-fall, comprising a supporting element, a receptacle thereon for finely granulated sand and having a discharge slot and a distributing ledge below said slot, and a receiving receptacle below the first named receptacle.

2. A device for imitating a water-fall, 90 comprising a supporting element, a receptacle thereon for finely granulated sand and having a discharge slot and a distributing ledge below said slot, and a receiving receptacle below the first named receptacle, and 95 a removable collecting receptacle into which said receiving receptacle discharges.

In testimony whereof I affix my signature in presence of two witnesses.

KARL WILHELM HEINRICH SCHROEDER.

Witnesses:

EMIL GROSSERY,
RICHARD WINKLER.
